(57) CLAIM

The ornamental design for an outdoor game, as shown and described.

DESCRIPTION

FIG. 1 is a top perspective view of the outdoor game; FIG. 2 is a top plan view of the outdoor game;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines in the drawings are for the purpose of illustrating portions of the outdoor game and form no part of the claimed design.
